UNITED STATES PATENT OFFICE

EDWARD B. HESS, OF NEW YORK, N. Y., ASSIGNOR TO ROYAL TYPE-WRITER COMPANY, OF HOBOKEN, NEW JERSEY, A CORPORATION OF NEW JERSEY.

WRITING-MACHINE.

No. 858,179.

Specification of Letters Patent.

Patented June 25, 1907.

Application filed January 30, 1905. Serial No. 243,441.

To all whom it may concern:

Be it known that I, EDWARD B. HESS, a citizen of the United States, residing in the borough of Brooklyn, city and State of New York, have invented certain new and useful

Improvements in Writing-Machines, of which the following is a specification.

This invention relates primarily to that class of typewriting machines in which either the platen or type bar segment is shifted up and down to print upper and lower case, and in which the impressions successively made are visible to the operator.

In the present instance the invention is shown embodied in a machine having a vertically shifting platen.

The invention comprises certain new features of construction and operation relating to locking and shifting the movable member.

The drawing, which shows the invention in a form that experience has demonstrated to be practicable and efficient, illustrates only so much of a writing machine as is desirable for the purpose of disclosing the invention.

Figure 1 is a vertical longitudinal section just inside of the side plate at the left of the machine; Fig. 2, a like section, with the parts in a different position; Fig. 3, a like section with the parts in still another position; Fig. 4, a similar section taken at the opposite side of the machine; Fig. 5, a bottom plan; Fig. 6, a detailed view showing the base rail of the carriage and adjustable stop at each side of the machine upon which it rests; and Fig. 7, a detail sectional view showing a modification.

The carriage, which may be of any appropriate type, is carried by horizontally disposed parallel links *a*, *b*, (there being one pair at each side of the machine) whose outer ends are connected by vertically disposed links *c*. The upper links *a*, *a*, are rigidly connected with a rock shaft *d* extending between the side plates of the machine.

At the right hand side of the machine (Fig. 4) there extends downwardly from the rock shaft an arm *e* to which is attached one end of a spring *f*, the opposite looped end of which engages either one of a series of teeth *g* on the edge of an adjustable plate *g'* pivoted upon the side plate of the machine and set in desired position by a slot and set-screw. The reaction of this spring,

counterbalances the weight of the carriage; and the tension of the spring is susceptible of adjustment by rocking plate *g'* and by transferring the looped end of the spring to different teeth thereon.

h is the bottom or base rail of the carriage; *h'* the upper rail; and between the two is a ball race. It is deemed unnecessary to show any further support for the carriage as any usual or appropriate construction may be adopted.

The base rail *h* may extend beyond the plates, and, as shown in Fig. 6, each side plate *i* has in it a recess in the bottom of which is seated a screw bolt *i'* provided with a lock nut, constituting an adjustable bottom rest or support for the rail.

On the vertical link *c*, at the left hand side of the machine, is attached an angle plate *j*, the upwardly extending end of which is formed with a locking notch *j'* normally engaged by a latch *k* pivoted on the side plate of the machine and having a horizontally extending lug *k'* that fits in the notch *j'*. A link *m*, pivotally attached to the latch *k*, extends forward horizontally and is pivotally connected at *m'* with the lower part of the inner end of an arm *n* secured to and extending rearwardly from a rock shaft *o* turning in bearings in the side plates at the front of the machine.

A spring *o'* applied around the rock shaft serves, by its reaction, to normally hold the arm *n* in the elevated position shown in Fig. 1. At the left hand side of the machine, an arm *p*, extends downwardly from the rock shaft *d* and has at its end a headed stud *p'* around which is loosely hooked the bent end of a link *q* which extends toward the front of the machine and is pivotally connected at *q'* with the upper part of the rear end of the arm *n*.

The flat stem *r* of a shift key *r'* extends through a slot in the stepped keyboard plate and also through a slot in a guide plate *r*²; and its lower end is pivotally connected at *r*³ with the arm *n* near its rear end. The cross pin *r*⁴ in the stem below the guide plate *r*² serves to limit the upward movement of the stem.

Downward movement of the carriage is, as stated, limited or determined by the stops *i'*. Upward movement is limited or determined by horizontally projecting arms or bolts *s*, one at each side of the machine, that abut against adjustable screw stops *s'* mounted on

the side plates. In the normal or lower position of the carriage in which it is locked by engagement with the latch *k* with the angular locking plate *j*, a straight line, connecting the axis of the shaft *o* with the axis of the pivotal connection between the rod *m* and the latch *k*, is above the pivotal connections *m'* between the link *m* and arm *n*, while a straight line, connecting the axis of the rock shaft *o* with the axis of the stud *p'*, lies below the connection *q'* of the link *q* with the arm *n*. When, therefore, the shift key *r'*, at the left hand side of the machine, is depressed, the link *m* is drawn forwardly, disengaging the latch *k* from the locking plate *j*, thereby releasing or unlocking the carriage. At the same time link *q* is moved rearwardly, its hooked end merely slipping upon the stud *p'*. This behavior of the parts is illustrated in Fig. 2. Continued depression of the key and of the arm *n*, which is moved downwardly by it, draws link *q* toward the front of the machine and the strain thereof exerted upon the arm *p* actuates the rock shaft *d* and shifts or elevates the carriage. The strain upon the link *q*, on elevation of the carriage, is exerted just after the pivotal connection *q'* passes below the straight line connecting the axes of *p'* and the rock shaft *o*, and consequently the action is that of a reverse or breaking toggle; and therefore the initial resistance opposed to the depression of the shift key at this stage of the operation is reduced to a minimum, movement of the carriage at that time when its inertia is being overcome being slowest, and the speed at which it is elevated being accelerated as the pivotal point *q'* passes downward. This feature of the construction, taken in connection with the counterbalancing of the machine by means of the spring *f*, affords a very light and uniform touch for the shift key.

The purpose of employing a rock shaft *o*, instead of merely providing the arm *n* at the left side of the machine, with a pivotal connection, is to permit the use of another shift key at the right hand side of the key board. This is illustrated in Fig. 4 which shows a shift key *t* whose stem *t'* is pivotally connected with an arm *t''* secured to and extending rearwardly from the right hand end of the rock shaft. Depression, therefore, of either shift key, *r'* or *t*, equally effects, first, unlocking and then shifting of the carriage or platen.

In order to lock the carriage in elevated position for continued printing of the upper case characters, the arm *t''* is extended rearwardly beyond its pivotal connection with the stem of the shift key and is provided with a laterally projecting adjustable eccentric screw bolt or lug *u*, which, when the shift key is depressed, may be engaged by the lower end of a pivoted lever *v* normally retracted by a spring *v'* but which may be thrown for-

ward over the lug *u* to lock the carriage or platen in elevated position by means of its upper end which is located at the right of the keyboard. When the carriage has been elevated by depression of either shift key and has been so locked it may be released by merely pressing upon the right hand shift key *t* such pressure, by reason of the tension exerted upon shaft *o*, or the minute yielding of other parts, is sufficient to so reduce or eliminate the frictional contact between lug *u* and the lower end of the lever *v* as that the light spring applied to the lever, and normally tending to retract it, will return it to normal position and thereby permit the carriage to descend when pressure upon the shift key is released.

In Fig. 7 is shown a modified means of accomplishing the described operations. In lieu of lever arm *n*, a bell crank lever *w* is secured to shaft *o*. Stem *r* is applied to its upper horizontal arm; link *m* is connected at *w* to the end of its downwardly extending arm; and link *q* is applied to the latter arm at *w'* between shaft *o* and the point *w'*. Owing to the different lengths of the arcs described by the points *w'*, *w*, when pendent arm of the bell crank moves toward the front of the machine, latch *k*, *k'* will first be removed from *j*, *j'*, and then link *q* will operate to swing arm *p* and elevate the carriage.

The arrangement herein described of employing a forwardly moving draw bar to shift the carriage has the advantage not only of economy of space but makes it permissible to shift the carriage by a finger piece at each side of the key board (without the use of the ordinary long key levers), to lock the shifted carriage and readily release it by pressure on either shift finger piece.

I claim as my invention.

1. The combination with the shifting member of a typewriting machine, of a shift key, and an operative connection between the key and said member comprising two pivotally connected links which, on the action of the shift key, act as a reverse toggle to thereby effect the shifting of said member.

2. The combination with the shifting member of a writing machine, of a flexing connection comprising two pivotally connected links arranged end to end and means for flexing the links as a reverse toggle to effect a shifting of said member.

3. The combination with the shifting member of a typewriting machine, of a latch locking the member in normal position, a rearwardly extending link rocking about a point located at the front of the machine, and two links pivotally connected therewith, one operatively connected with the latch and the other to said shifting member, and means for depressing the front link to thereby withdraw the latch and then shift said member.

4. The combination with the shifting mem-

ber of a typewriting machine, of a shift key, an operative connection between the key and said member comprising two pivotally connected links which, on the action of the shift key, act as a reverse toggle to thereby effect the shifting of said member, and a spring for counterbalancing the weight of the shifting member.

5. The combination with the shifting member of a writing machine, of a flexing connection comprising two pivotally connected links arranged end to end and means for flexing the links as a reverse toggle to effect a shifting of said member, and a spring for counter-

15 balancing the weight of the shifting member.

6. The combination with the shifting member of a typewriting machine, of a latch locking the member in normal position, a rearwardly extending link rocking about a point

20 located at the front of the machine, and two links pivotally connected therewith, one operatively connected with the latch and the other to said shifting member, and means for de-

25 pressing the front link to thereby withdraw the latch and then shift said member and a spring for counterbalancing the weight of the shifting member.

7. The combination of the shifting member of a typewriting machine, a latch locking it in

30 normal position, a rearwardly extending link rocking about an axis at the front of the machine, a link extending from the lower side of the first named link to the latch, and a link

35 extending from the upper side of the first named link to the shifting member, the point of connection between the first and second named links and the point of connection be-

40 tween the first and third named links, being respectively above and below a line joining the axis of the first named link and the point of connection between the shifting member

55 and its operating link.

8. The combination of the shifting member of a typewriting machine, of a latch locking it in normal position, a rearwardly ex-

45 tends link turning about an axis in the front of the machine, a link pivotally connected thereto and extending rearwardly to the latch, the two links constituting a toggle,

50 and the pivotal connection between the two being located to one side of the center line of the toggle, a third link pivotally connected to the first named link and extending rearwardly to the shifting member, said first and third

55 named links constituting a toggle and the pivotal connection between the two being located on the opposite side of the center line of the toggle, and means for swinging the first named link about its axis to thereby first op-

60 erate the latch and then move the shifting member.

9. The combination with the shifting member of a typewriting machine, of a rock shaft mounted at the front of the machine, an arm

65 or link extending rearwardly therefrom at

each side of the machine, a shift key operatively connected with each of said arms, and a link pivotally connected with one of said arms and extending rearwardly to the shifting member whereby said member may be shifted by depression of the shift key at either side of the machine.

10. The combination with the shifting member of a typewriting machine, of a rock

70 shaft mounted at the front of the machine, an arm or link extending rearwardly there-

from at each side of the machine, a shift key operatively connected with each of said arms, a link pivotally connected with one of said

arms and extending rearwardly to the shift- 80

ing member whereby said member may be shifted by depression of the shift key at either side of the machine, and a friction latch

85 adapted to engage one of said arms when depressed to thereby hold the shifting member in shifted position, and a spring for automatically withdrawing said latch when strain is exerted upon the rearwardly extending arm to which the latch is applied.

11. The combination with the shifting 90

member of a typewriting machine, of a rock

shaft mounted at the front of the machine, an arm or link extending rearwardly there-

from at each side of the machine, a shift key operatively connected with each of said arms, 95

a link pivotally connected with one of said arms and extending rearwardly to the shift- 100

ing member whereby said member may be shifted by depression of the shift key at either side of the machine, and a friction 105

latch adapted to engage one of said arms when depressed to thereby hold the shifting

member in shifted position, and a spring for automatically withdrawing said latch when pressure is exerted upon the shift key con- 110

nected with the rearwardly extending arm to which the latch is applied.

12. The combination with the shifting member of a writing machine of a latch lock- 115

ing it in normal position, a shift key and two

links operatively connected with the shift key, and with the latch and shifting member respectively, and having unequal endwise movement, whereby on depression of the key the latch is first disengaged from the shifting 120

member and then said member is shifted.

13. In a front-stroke writing machine, the

shifting member thereof adapted to shift ver-

125 tically, in combination with a shifting draw-

bar operatively connected with the shifting member and extending forward to the front of the machine, a part pivoted at the front of the machine and to which the draw-bar is

flexibly connected, and means applied over the connection formed by said part and draw- 130

bar to rock said part about its pivot and draw the draw-bar toward the front of the machine.

14. In a front stroke writing machine, the

combination of the shifting member thereof

- 4
- adapted to shift vertically, a shift key, a locking device for locking the shiftable member in normal position and an operative connection between the key and the shifting member and locking device, comprising three links two of which are movable endwise longitudinally of the machine whereby, on actuation of the key, the shiftable member is first unlocked and then shifted.
- 10 15. A writing machine comprising a shifting member, a latch for locking it in normal position, two forwardly extending links one connected to the latch and the other connected to the shifting member and a swing-
- ing part at the front of the machine with 15 which the front ends of such links are so connected that on actuation of such part the latch is first operated to release the shifting member by the endwise movement of one link and then said member shifted by the 20 endwise movement of the other link.
- In testimony whereof, I have hereunto subscribed my name.

EDWARD B. HESS.
